UNITED STATES PATENT OFFICE.

JOHN M. CRAIGO, OF HARTFORD, CONNECTICUT.

ATTACHMENT FOR TEETH.

Application filed December 10, 1924. Serial No. 754,946.

This invention relates to attachments for holding artificial bridges, plates, dentures or other orthodontia appliances in the mouth.

The aim of the invention is to provide an improved attachment of this sort having various features of novelty and advantage, and which is particularly characterized by its practicability and effectiveness in use in that the denture or bridge work is maintained in proper relation to the permanent teeth with which it is associated, and the attachment may be readily removed from, and replaced into, position.

By the use of my improved arrangement, the artificial teeth or bridge work is held against tilting and pivotal movements while, at the same time, there is sufficient resiliency present to permit all of the teeth to function properly.

My improved attachment is very simple in construction, economical in manufacture and may be readily applied to any of the permanent teeth in the mouth without in any way mutilating or damaging such teeth.

My attachment may be correctly fitted to teeth which are irregular or abnormally inclined.

A further aim of the invention is to provide an improved attachment which is so neat in appearance that it will hardly be observed, even when applied to the front teeth, in the mouth.

My improved arrangement is such that crevices, cracks or the like, in which particles of food or other foreign matter may lodge, are substantially eliminated; undue strains on the permanent teeth, to which the attachment is applied, are avoided; and there may be such relation between the bridge work and the gum that the latter is maintained in proper condition.

Other objects will be in part obvious and in part pointed out more in detail hereinafter.

The invention accordingly consists in the features of construction, combination of elements and arrangement of parts which will be exemplified in the construction herein-after set forth, and the scope of the application of which will be indicated in the appended claims.

In the accompanying drawing, wherein I have shown, by way of illustration, one embodiment which the present invention may take;

Figure 1 is a front view showing a den-

ture or appliance attached to two permanent teeth;

Fig. 2 is a perspective view showing a clasp in position to be slipped over the crown;

Fig. 3 is a sectional view through a crown and a clasp applied thereto, the tooth which the crown caps being shown in elevation, this view being taken substantially on line 3—3 of Fig. 1;

Fig. 4 is a view similar to Fig. 3, but taken substantially on line 4—4 of Fig. 1; and

Fig. 5 is an enlarged detail view taken through one arm of the clasp, substantially on line 3—3 of Fig. 1, the crown being shown in outline by dotted lines.

In these drawings, I have shown a bridge carrying two artificial teeth and having at each end a clasp respectively associated with two crowned permanent teeth, but it is to be understood that this showing is by way of exemplification only and it is not to be taken as restrictive of my conception, it being obvious that the denture or orthodontia appliance may be of any desired form depending upon conditions, and that the denture may be held in place by a single clasp. For purposes of brevity and convenience in description, the orthodontia appliance, plate or denture will be referred to as a "bridge", it being understood that this term is employed in its generic sense.

Referring to the drawing in detail *a* denotes one of the jaws of the mouth; *b*, permanent teeth; and *c*, *c*, crowns for the permanent teeth. Between the permanent teeth *b* are removable or artificial teeth *d* fixed to a plate or bridge *e* having at each end a clasp *f*.

Each of the clasps may be in the form of a particular band adapted to partially encircle the crowns on the permanent teeth. In the present instance, each clasp is shown as having a pair of arms 10 adapted to closely straddle a crown, the clasp, by preference, being made of a suitable resilient material so that the arms may spring slightly apart when slipping the clasp onto a crown or removing the same therefrom and so that the arms will hub the crown when the clasp is in position. Each of the clasps may have a tang or wing 11 by means of which it is secured to the bridge *e* or the clasps may be formed integrally with the plate.

In accordance with the present invention,

each arm of a clasp is provided with a depression or recess 12, and these recesses are adapted to closely receive similarly shaped projections 13 on opposite sides of a crown

5 c. By preference, each arm is further provided with a second recess or depression 14 which, when the clasp is in place on the crown, is adapted to receive or fit over a respective projection 15 on the crown. It is 10 desirable that these depressions 14 be immediately beneath the recesses 12 and that they be opened at their lower edges so as to form grooves, so to speak. The projections 15 are immediately below the projections 13. 15 It will be observed that, with this arrangement, the clasp may be readily slipped into place on the crown for, when it is moved down into position, the grooves 14 will accommodate the projections 13, resulting in 20 the arms being slightly cammed apart so that the clasp will slip over the projections 13 until these projections are received by the recesses 12. When the clasp is in final position, the projections 13 fill the grooves 25 or depressions 14 so that food or other foreign matter cannot lodge therein. Owing to the fact that the arms are hugging the crown, and the projections 13 are engaged in the recesses 12, the attachment is held 30 against accidental displacement or withdrawal from the crowns. It will further be observed that each of the arms is maintained in position with respect to the crown by two projections on the latter, namely a 35 projection 13 and a projection 15. This means that each clasp is held against a tilting action in one direction and a pivotal action in the other direction.

For the purpose of relieving excessive 40 stress on the gum tissue, particularly where the bridge or plate is relatively small, each clasp may be positively held against moving down to too great an extent on the crown with which it is associated. For example, 45 each crown may be provided on opposite sides with a projection or boss 17, and each arm may have in its lower edge a notch 18 adapted to receive one of these bosses. By preference, the bosses 17 fit closely within 50 the recesses so as to eliminate spaces in which food or the like might lodge. The projections and bosses of the crowns are economically formed by bending the metal of the crown outwardly by means of suitable dies. The top or end surface of the boss 17 forms a relatively abrupt shoulder or flat

ledge, and the upper or inner edge of the notch 18 securely seats upon this ledge. Thus, there is no tendency for the ledge to cam the arms apart.

What I claim is:—

1. In combination, a crown having on each of two of its opposite sides a boss provided with a pronounced shoulder adapted to form a stop and rest at its upper end, and a clasp having a pair of resilient arms hugging said crown and each provided at its lower edge with a notch, the inner edge of which securely seats on a respective boss, and said clasp being in its normal position freely slidable upwardly out of engagement with said boss when it is desired to remove the clasp from the crown. 60

2. In combination, a crown having on one side face a projection and also having on one side face a boss adapted to form a stop and rest, and a clasp having a pair of arms straddling said crown, one of said arms resting on said boss and one of said arms being provided with a recess receiving said projections and interlocking therewith to prevent accidental withdrawal of the clasp from the crown and said clasp being in its normal condition freely slidable upwardly out of engagement with said boss when it is desired to remove the clasp from the crown. 70

3. In combination, a crown having a projection and a boss on each of two of its opposite sides, and a clasp having a pair of arms straddling said crown and respectively resting on said bosses, each of said arms being provided with a recess closely receiving one of said projections. 80

4. In combination, a crown having on each of two of its opposite sides a plurality of projections, and a clasp having a pair of resilient arms hugging said crown and each provided with a plurality of recesses respectively receiving said projections, said crown having on each of said sides a boss and said arms respectively resting on said 90 bosses. 100

5. In combination, a crown having on each of two of its opposite sides a pair of projections and a boss, and a clasp having a pair of resilient arms hugging said crown and each provided with a pair of recesses respectively receiving said projections, said arms being provided with notches respectively receiving said bosses. 105

JOHN M. CRAIGO.
